CLAIM

The ornamental design for an emergency light, as shown and described.

DESCRIPTION

FIG. 1 is a front elevational view thereof;
FIG. 2 is a left side elevational view with the right side being a mirror image thereof;

FIG. 3 is a rear elevational view thereof;

FIG. 4 is a top view thereof; and,

FIG. 5 is a bottom view thereof.

The broken-line showing of the words, "The Emergency Light", is for illustrative purposes only and forms no part of the claimed design.
